(57) **CLAIM**

The ornamental design for an aiming and illumination device as shown and described.

DESCRIPTION

FIG. 1 is a top front right perspective view of a first embodiment of an aiming and illumination device;
FIG. 2 is a top rear left perspective view of the first embodiment of the aiming and illumination device;
FIG. 3 is a front elevational view of the first embodiment of the aiming and illumination device;
FIG. 4 is a rear elevational view of the first embodiment of the aiming and illumination device;
FIG. 5 is a right side elevational view of the first embodiment of the aiming and illumination device;
FIG. 6 is a left side elevational view of the first embodiment of the aiming and illumination device;
FIG. 7 is a top plan view of the first embodiment of the aiming and illumination device; and
FIG. 8 is a bottom plan view of the first embodiment of the aiming and illumination device.

FIG. 9 is a top front right perspective view of a second embodiment of an aiming and illumination device;
FIG. 10 is a top rear left perspective view of the second embodiment of the aiming and illumination device;
FIG. 11 is a front elevational view of the second embodiment of the aiming and illumination device;
FIG. 12 is a rear elevational view of the second embodiment of the aiming and illumination device;
FIG. 13 is a right side elevational view of the second embodiment of the aiming and illumination device;
FIG. 14 is a left side elevational view of the second embodiment of the aiming and illumination device;
FIG. 15 is a top plan view of the second embodiment of the aiming and illumination device; and,
FIG. 16 is a bottom plan view of the second embodiment of the aiming and illumination device.
The evenly broken lines in the drawings depict unclaimed portions of the aiming and illumination device; the dash-dot broken lines disclose unclaimed boundaries of the claim; the broken lines form no part of the claimed design.
